US00D553188S

(12) **United States Design Patent** (10) **Patent No.:** **US D553,188 S**
DaBoll (45) **Date of Patent:** **** Oct. 16, 2007**

(54) **CRAYON FOR DEVELOPING DYNAMIC
TRIPOD GRIP**

(76) Inventor: **Barbara Lee DaBoll**, 2900 Mayfield Ave., La Crescenta, CA (US) 91214

(**) Term: **14 Years**

(21) Appl. No.: **29/243,851**

(22) Filed: **Nov. 30, 2005**

(51) **LOC (8) Cl.** 19-06

(52) **U.S. Cl.** D19/41

(58) **Field of Classification Search** D19/35, D19/36, 41-51, 53, 54-57, 65, 73, 96, 97; D1/100, 127; D6/601; D8/300, 310; D11/131, D11/157, 158; D14/402, 410; D24/101, D24/104, 214-215; D28/8.1, 8.2; 5/622, 5/630, 636; 401/52, 99-100, 104-109, 192, 401/195, 243-247, 6; 40/334; 428/15

See application file for complete search history.

(57) **CLAIM**

The ornamental design for crayon for developing dynamic tripod grip, as shown and described.

DESCRIPTION

FIG. 1 is a perspective view of a crayon according to the present invention;

FIG. 2 is another perspective view of a crayon according to the present invention;

FIG. 3 is a top view of a crayon according to the present invention;

FIG. 4 is a side view of a crayon according to the present invention;

FIG. 5 is a bottom view of a crayon according to the present invention;

FIG. 6 is a front view of a crayon according to the present invention;

FIG. 7 is another side view of a crayon according to the present invention; and,

FIG. 8 is a rear view of a crayon according to the present invention.
